UNITED STATES PATENT OFFICE.

SAVVA Y. JOHNSON, OF CHICAGO, ILLINOIS.

DESIGN FOR SILK FABRIC.

No. 39,148.

Specification for Design.

Patented Feb. 18, 1908.

Application filed January 9, 1908. Serial No. 410,064. Term of patent 7 years.

To all whom it may concern:

Be it known that I, SAVVA Y. JOHNSON, a subject of the Sultan of Turkey, residing at Chicago, county of Cook, and State of Illinois, United States of America, have invented a new, original, and ornamental Design for Silk Fabric, of which the following is a specification, reference being had to the accompanying drawing, forming a part thereof.

The figure is a view of a piece of silk fabric, showing my new design.

I claim:
The ornamental design for silk fabric, as shown.

SAVVA Y. JOHNSON.

Witnesses:

FRANCES E. SHEEHY,
HELEN F. LILLIS.
